UNITED STATES PATENT OFFICE.

JOSEPH HUNDAUSEN, OF SCHOFIELD, WISCONSIN.

SPLIT SHAFT FOR USE ON PAPER-MACHINES.

1,242,807.

Specification of Letters Patent.

Patented Oct. 9, 1917.

Application filed September 27, 1916. Serial No. 122,564.

To all whom it may concern:

Be it known that I, JOSEPH HUNDAUSEN, a citizen of the United States, residing at Schofield, in the county of Marathon and State of Wisconsin, have invented certain new and useful Improvements in Split Shafts for Use on Paper-Machines; and I do hereby declare the following to be a full, clear, and exact description of the invention, such as will enable others skilled in the art to which it appertains to make and use the same.

The present invention relates to improvements in split shafts for use on paper machines, in which the shaft is built up of relatively movable sections, and there is means provided to expand and collapse the sections in order to engage and remove the shaft from the paper core.

An object of the present invention resides in providing improved means whereby the shaft is so expanded and collapsed and, broadly stated, this means consists in an axially-shiftable rod passing through the shaft and having successively offset sections disposed in relatively opposite directions and being connected by inclined joints, for coöperating with perforated lugs on the shaft sections.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views:

Figure 1 is a side elevation, partly in section, of an improved split shaft constructed in accordance with the present invention and being in the expanded condition.

Fig. 2 is a longitudinal sectional view illustrating the same in the collapsed position.

Fig. 3 is a cross sectional view on an enlarged scale through the line 3—3 in Fig. 1; and

Fig. 4 is a similar view on the line 4—4, likewise in Fig. 1.

Referring more particularly to the drawings, 1 and 2 designate the semi-cylindrical sections of which the holding device is made up. Any number of sections may be employed, as will be obvious to those skilled in this art.

To the section 1 are attached the perforated lugs 3, and to the section 2 similar lugs 4; the latter being placed substantially midway between the lugs 3. A rod or shaft 5 extends through the perforations in the lugs 3 and 4, and is formed with the successively-offset sections 6 and 7 in relatively opposite directions. These offsets 6 and 7 are connected together through the inclined joints 8 and 9, which, together, preferably form one piece.

The rod 5 is shiftable axially through the holding device, as by a handle 10; this handle being connected to the rod in any suitable manner. The rod is held in an initial position, which is that corresponding to the expanded condition of the members 1 and 2, by a coil spring 11 surrounding the reduced end 12 of the rod and bearing at one end against a head 13 adjustably held by a nut 14 threaded on said end 12. By this means the tension on the spring may be varied as required. The other end of the spring 11 engages a head 15 secured to some longitudinally-stationary part as the member 1, and is formed with a slot 16 to permit the necessary movement of the member 1.

There are also preferably guides, being half-circular collars 17 and 18, secured respectively to the members 1 and 2, and having a lap joint including the offset tongues 19 and 20 working in the side recesses 21 and 22.

In operation, the device being in the expanded position shown in Fig. 1 and it being desired to collapse the same preparatory to insertion in the paper core, the handle 10 is grasped and pulled out to the position shown in Fig. 2. This will shift the rod 5 axially through the members 1 and 2 in such manner as to cause the inclined joints 8 and 9, etc., to ride through the perforations in the series of lugs 3 and 4 and to shift one of the offset portions out of, and an adjacent offset portion into engagement with the respective lug; having the effect, as will clearly appear from a comparison of Figs. 1 and 2, of drawing in the holding members 1 and 2. The guides will preserve the relative positions of the two members.

When so collapsed the device is inserted within the core and the handle 10 thereupon released. Subsequent to this the coil spring 11 will come into play, operating against the head 13 to return the rod 5 to initial position, and so moving the offsets 6 and 7 and

joints 8 and 9 relatively to the lugs 3 and 4 as to force the members 1 and 2 apart, when they will effectively grip the core. The device is mounted in connection with the driving element in any approved manner.

It is obvious that those skilled in the art may vary the details of construction and arrangements of parts without departing from the spirit of my invention, and therefore I do not wish to be limited to such features except as may be required by the claims.

I claim:

1. An apparatus for holding paper rolls including relatively-movable core-gripping members, a rod passing between said members and having portions successively offset in different directions with inclined joints connecting the offset portions, means for moving said rod, and means coupled between said members and the offset portions of said rod and engageable by said inclined joints to expand and collapse said members, substantially as described.
2. An apparatus for holding paper rolls including relatively-movable core-gripping members, an axially shiftable rod passing between said members and having portions offset in successively different directions, inclined joints connecting said offset portions, means for shifting said rod axially, and means coupled between said members and the offset portions of said rod and engageable by said inclined joints to expand and collapse said members, substantially as described.

Copies of this patent may be obtained for five cents each, by addressing the "Commissioner of Patents, Washington, D. C."

3. An apparatus for holding paper rolls including collapsible core-engaging members, a rod having offset portions and inclined joints connecting said offset portions, means for moving said rod, and lugs on said members having openings therein for receiving said rod whereby to contract the members when the rod is moved in one direction and expand said members when the rod is moved in the opposite direction, substantially as described.

4. An apparatus for holding paper rolls including contractile core-engaging members, a rod having portions offset in successively opposite directions and inclined joints between said offset portions, means for shifting said rod, means for yieldably holding said rod in an initial position, and means between said members and rod for riding over the inclined joints from one to the adjacent offset portion whereby to expand or collapse said members, substantially as described.

5. An apparatus for holding paper cores including collapsible core-engaging members, means for expanding and contracting said members, and guide collars for said members having a lap joint, substantially as described.

In testimony whereof, I affix my signature.

JOSEPH HUNDHAUSEN.
